ASH REMOVING AND RECEIVING DEVICE

John P. Dennebaum, Scranton, Pa.

Application August 24, 1942, Serial No. 455,920

2 Claims. (Cl. 280—59)

This invention relates to ash receiving and removing devices for furnaces.

An object of this invention is to provide a metallic pit forming structure for mounting below a furnace in which a dolly is adapted to be mounted, the dolly being constructed to receive an ash can, and the dolly being arranged so that it may be pulled out of the pit and moved to any suitable point for disposal of the ashes.

Another object of this invention is to provide an improved pit forming structure which also constitutes a runway or guide for the dolly and which may be embedded in the ground below the furnace.

A further object of this invention is to provide a structure of this kind which includes an ash guiding means for guiding the dropping ashes into a collector or receiver which is mounted on a removable dolly.

A further object of this invention is to provide a structure of this kind which may be mounted beneath the present construction of a furnace so as to facilitate the removal of ashes.

A further object of this invention is to provide a structure of this kind which may be used with either manually fed or mechanically fed furnaces and which will eliminate the creation of dust around the furnace during the removal of the ashes, as is at present the case.

It is known that devices of this kind have been produced which provide for pulling of the dolly and ash receiver from the pit coincident with the raising of the trap door, but such devices have the disadvantage of not permitting the use of the dolly in transferring the receiver to a point remote from the furnace. With a construction of this kind, the dolly and receiver may be shifted to any desired remote point, and the receiver lifted from the dolly and then returned to the pit with an empty receiver, thus making it unnecessary for the user of this structure to immediately remove the ashes from the receiver.

In the drawing:

Figure 1 is a detail top plan of an ash removing structure constructed according to an embodiment of this invention.

Figure 2 is a sectional view taken on the line 2—2 of Figure 1, and

Figure 3 is a top plan partly broken away of the ash receiver dolly.

Figure 4 is a sectional view taken on the line 4—4 of Figure 3.

Referring to the drawing, the numeral 10 designates generally a furnace of conventional construction which is provided with an ash pit 13 in

the lower portion thereof. A pit forming structure generally designated as 11 is adapted to be disposed below the furnace 10 with a portion thereof projecting either forwardly or laterally of the furnace, and the pit forming structure 11 is adapted to be embedded in the ground and extended below the floor 12 upon which the furnace 10 is adapted to rest.

The pit forming structure 11 includes a bottom wall 14 which is formed of a horizontally disposed rear part 15 and an obtusely disposed upwardly and outwardly extending forward part 16. A vertically disposed rear wall 17 extends upwardly from the rear end of the rear part 15 and vertically disposed side walls 18 extend upwardly from the bottom wall 14 and the side walls 18 are secured to the opposite vertical edges of the rear wall 17. The forward part 16 of the bottom wall 14 is formed with a flange or horizontally disposed upper end portion 19 which may be embedded in the floor 12, adjacent the upper surface of the floor.

A top wall 20 is mounted on the upper edges of the pit forming member 11 and is provided with an opening 21 forming an entrance or exit for a dolly to be hereinafter described. The side walls 18 may be formed with horizontally disposed and laterally extending flanges 22 which are adapted to be embedded or secured in the floor 12 and the top wall or plate 20 is adapted to rest or be secured to the flanges 22 and 19. A door or closure 23 is hingedly secured as at 24 to the top wall 20 and is formed adjacent the forward portion thereof with a detent or depression 25 with which a U-shaped handle 26 is adapted to engage. The handle 22 is loosely mounted through the plate or closure 23 and is adapted to be lifted upwardly to an operative position and to the limit provided by means of stop members 27 which are secured to the opposite legs of the U-shaped handle 26 below the plate or closure 23.

The plate or top wall 20 at a point below the ash pit 13 of the furnace 10 is formed with a downwardly tapering ash guiding member, generally designated as 28. The ash guiding member 28 includes oppositely disposed side flanges 29 and 30 which are disposed in downwardly convergent relation and forward and rear flanges 31 and 32 which are also disposed in downwardly convergent relation and secured at the opposite ends thereof to the flanges 29 and 30.

A dolly generally designated as 33 is adapted to be removably disposed in the pit forming structure 11 and includes a frame structure formed of a pair of rearwardly divergent arms 34 and

35 and a forwardly extending arm 36 which extends forwardly from the convergent ends of the arms 34 and 35. Each of the arms 34 and 35 as shown in Figure 2 includes an upwardly offset rear portion 37 connected to the central portion of the arm by means of a vertically disposed connecting member 38. A depending wheel bearing member 39 is secured to the lower side of each of the pair of arms 34 and 35 and a wheel 40 is rotatably carried by the bearing member 39.

The forward arm 36 is formed with an upwardly offset forward portion 41 connected to the main portion of the arm 36 by means of a vertically disposed connecting member 42. A front wheel bearing 43 is rotatably mounted about a vertical axis below the offset portion 41 and has a wheel 44 rotatably secured thereto. The bearing 43 includes an upwardly extending shaft 45 which extends through the offset portion 41, and a U-shaped handle mounting member 46 is secured to the upper end of the stub shaft 45. An elongated handle 47 is pivotally secured at its rear end as at 48 between the flanges or arms of the bearing 46 and the forward end of the handle 47 may be provided with a hand grip member 49. The hand grip member 49 is adapted to be positioned closely adjacent the upper end portion of the forward part 16 of the bottom wall 14 when the dolly 33 is positioned within the pit 11.

The vertical connecting members 38 and 42 with the main portions of the arms 34, 35 and 36 form a seat portion on which an ash receiver 50 is adapted to removably engage. The ash receiver 50 when in receiving position is adapted to be disposed directly below the guide member 28 so that the ashes shaken down from the grates of the furnace 10 will drop through the guide member 28 and into the receiver 50.

In the use and operation of this structure, the pit or pit forming member 11 is adapted to be embedded in the ground and secured within the floor 12 so that the horizontal wall 15 will be positioned below the ash pit 13 of the furnace 10. The dolly 38 with the receiver 50 mounted thereon is then positioned within the lower portion of the pit 11. The door or closure 23 will be normally closed so that the dust raised by the dropping of the ashes from the furnace 10 into the receiver 50 will not rise into the body of the cellar.

When it is desired to remove the receiver 50, the door or closure 23 is raised to the dotted line position shown in Figure 2. The hand grip 49 may then be gripped and the dolly 33 may then be pulled upwardly along the upwardly extending bottom wall part 16 which constitutes the runway for the pit. The receiver 50 may then be moved while positioned on the dolly 33 to any desired remote position with respect to the furnace 10 and then lifted off of the dolly 33. In the event the user of this device employs additional receivers 50, the filled receiver may be placed in a desired location for collection and the empty receiver then placed on the dolly 33, whereupon the latter may be returned to the pit 11 and the door or closure 23 closed.

The ash removing structure hereinbefore described is of simple construction so that it may be manufactured and sold at small cost and when in use will provide a structure which will eliminate in great part the generation of dust from the ashes within the body of the cellar or the room within which the furnace 10 is located.

What I claim is:

1. A wheeled truck comprising a frame formed of a pair of rearwardly divergent arms and a forwardly extending arm extending from the convergent ends of said pair of arms, each arm including an inner horizontal member, a vertical extension at the outer end of each horizontal member, and an outer horizontal member, parallel wheel bearings carried by the rear pair of said outer members, wheels rotatably carried by said bearings, an inverted U-shaped front wheel bearing, a stub shaft carried by said front bearing journaled through the front outer member, a U-shaped member secured to said stub shaft on the upper side of said front outer member, the bight of said U-shaped member rotatably engaging said upper side and holding said stub shaft against downward movement, an elongated handle, and means rockably securing said handle between the arms of said U-shaped member.

2. A wheeled truck as set forth in claim 1 wherein said inner horizontal members are substantially longer than said outer members to thereby form a downwardly offset article seat, said vertical extensions providing means to hold the article against lateral movement.

JOHN P. DENNEBAUM.
